UNITED STATES PATENT OFFICE.

HENRY P. APPLETON, OF NORWICH, CONNECTICUT.

KNOB ATTACHMENT.

SPECIFICATION forming part of Letters Patent No. 331,752, dated December 8, 1885.

Application filed March 27, 1885. Serial No. 160,148. (No model.)

To all whom it may concern:

Be it known that I, HENRY P. APPLETON, a citizen of the United States, residing at Norwich, in the county of New London and State 5 of Connecticut, have invented a certain new and useful Improvement in Knob Attachments, which improvement is fully set forth and described in the following specification, reference being had to the accompanying drawings, in which—

Figure 1 is a vertical sectional view of a portion of a door having a lock-case in proper position, and also showing my improved method of connecting the knob-necks, the hub-spindle being partially cut away to expose the locking-key. In Fig. 2 I have shown detached top views of the knob-necks and the hub-operating spindle.

My invention relates to that class of knob attachments in which the spindle is threaded at its angles, in order that an internally-threaded knob-neck may be screwed thereon to adjust the knobs to doors of different thickness, my immediate object being to provide a convenient and inexpensive means for locking the adjustable neck to the spindle after the knobs are in the desired position in the door.

In the annexed drawings, A represents the door, B the lock-case seated in its mortise, and 30 C the bolt-operating hub, having the usual central rectangular opening.

aa' represent the knob-necks, and b the hub-operating spindle, one of whose ends is preferably fastened rigidly in neck a'. Said spindle is threaded at its angles throughout the greater portion of its exposed part, as shown in the drawings, and the knob-neck a is provided with a circular central hole threaded to engage the threaded spindle. Spindle b is 40 slotted longitudinally, as at e, to receive a locking-key, e, said key and the means shown for locking it in a given position being the vital parts of this present invention. Key e is so located and pivoted in a slot in neck a that its free 45 sector-shaped end may be forced downward into slot e, to prevent the neck from rotating on the spindle, in which position the outer edge of said key is flush with the periphery of the knob-neck. After the several other 50 parts are properly adjusted the rose or escutche-

on E is slipped forward into place and secured to the door by any of the means in common use.

To prevent all tendency on the part of the key to work loose, I have drilled the shell of 55 the neck a longitudinally, and have placed therein a spring, d, and plug f, said spring acting with a constant tendency to force plug f forward into engagement with the edge of the key; and to further provide means 60 for retaining the key in either an open or closed position, I have provided in the edge of the key notches or depressions i i', one of which furnishes a seat for plug f when said key is raised and thrown out of engagement with the slotted spindle, (see dotted lines, Fig. 1,) the other notch being adapted to engage said spring-pressed plug to hold the key in its lowered position. Said key is 65 cut under slightly at its outer upper end, and 70 the neck is cut transversely, so that a fingernail or sharp instrument may be easily used to raise the key when desired.

To operate my device, pass the spindle through the hub C until the fixed neck a' abuts against said hub, as in Fig. 1. The rose E is now slipped onto neck a, and with the key raised, as in dotted lines, Fig. 1, said neck is screwed onto the threaded spindle until it also abuts against the hub C. The 80 key is now forced downward until its upper notch, i, engages the spring-pressed plug f, and the rose is slipped forward and fastened to the door.

I am aware that spindles with threaded 85 angles engaging internally-threaded knob-necks have been used to provide the necessary adjustment to doors of different thicknesses, and do not, therefore, broadly claim such a means for adjustment.

What I claim as new, and wish to secure by Letters Patent, is—

1. In combination with a longitudinally-slotted hub-spindle whose angles are threaded, and an internally-threaded knob-neck adapted 95 to engage said spindle, a key pivoted in a longitudinal slot in the knob-neck and capable of entering the longitudinally-slotted spindle, to prevent said spindle from rotating within said knob-neck, and means for retaining 100

said key in engagement with the spindle-slot, all substantially as herein described.

2. In combination with a hub-operating spindle having threaded angles, a knob-neck 5 internally threaded to engage said spindle, a key so pivoted in the knob-neck that it may be forced into the spindle-slot, and a spring-pressed plug located in the knob-neck and

adapted to engage notches *i i'* in the sector-shaped edge of the key, all substantially as to described, and for the objects set forth.

HENRY P. APPLETON.
